UNITED STATES PATENT OFFICE.

ALBIN J. JOHNSON, OF DULUTH, MINNESOTA, ASSIGNOR OF ONE-HALF TO CARL HANSON, OF DULUTH, MINNESOTA.

COMBINATION TOOL.

Application filed March 24, 1921. Serial No. 455,228.

To all whom it may concern:

Be it known that I, ALBIN J. JOHNSON, a citizen of the United States, residing at Duluth, in the county of St. Louis and State 5 of Minnesota, have invented certain new and useful Improvements in Combination Tools, of which the following is a specification, reference being had therein to the accompanying drawing.

This invention relates to wrenches and has 10 special reference to a novel form of combination wrench and pliers.

The principal object of the invention is 15 to provide a more convenient instrument of this character than heretofore known.

Another object is to provide a device of this character which may be used not only as a pair of pliers or a wrench, but also as a small hand vise.

Still other objects and advantages will appear in the further description thereof.

Referring to the accompanying drawing forming part of this application and in 20 which like reference characters indicate like parts:

Figure 1 is a central sectional view of the combination instrument;

Fig. 2 is a side elevation of same; and

Fig. 3 is a transverse sectional view on the 25 line 3—3, Fig. 1.

The main body portion of the tool comprises the shank 1 and handle 2, which are of a single piece; and upon the outer end of the shank 1, formed integral therein, is 30 the fixed jaw 3 of the wrench. The jaw edge of the shank 1 has formed therein a longitudinally-disposed rectangularly-shaped channel, the same passing through the base of the jaw 3, and into which channel is slidably mounted the cogged rack 4 which 35 normally extends towards the jaw end of the wrench the full length of the channel, and upon such end is provided with an enlarged head 5 having a notch or recess 6 formed in 40 the face thereof away from the jaw 3. Into this notch is cooperatively engaged a lug or cog 7 which is an integral part of the head 8 of the arm 9 which is pivotally mounted at 45 10 in the bifurcated extension 11 of the head of the shank 1. Thus when the arm 9 is raised or lowered on its pivotal point 10, the rack 4 will be reciprocated back and forth as is obvious.

The arm 9 is provided with a handle-like

extension 12, parallel with the handle portion 55 2 of the wrench, and which completes said handle portion and is so shaped as to make a convenient grip for the hand of the operator.

Intermediate of the ends of the arm and 60 handle 9—12 is an integrally formed projection 13 which extends at practically right angles to the main portion of the arm so that the latter may be closed into a suitably formed opening or aperture through the 65 main body portion 1—2 of the wrench. The channel in which the rack reciprocates terminates in the lower end of the aperture, so that when the arm 9—12 is in its closed position against the main body portion of the 70 wrench and the rack 4 fully extended outwardly, the projection or key 13 will fill the aperture in the main body portion and act as a stop for the inner end of the rack 4 which will impinge against same during such time 75 as the wrench is being employed in engaging an object either as a wrench or when the jaws thereof are tightly impinged against the object.

A second adjustable jaw 14, such as are 80 common to similar wrenches, is reciprocally carried upon the shank 1 of the wrench and has rotatably mounted therein a short worm 15 on the pin 16 and which worm meshes with the teeth on the rack 4 and by rotating the worm 15 any desired variation in the 85 space intermediate of the jaws 3 and 14 may be accomplished, as is common to such devices.

By this arrangement it will be seen that 90 when it is desired to tightly engage for example a nut in either tightening or loosening same, the jaw 14 may be adjusted to approximately the proper size of the nut, when the handle 12 is separated from the handle portion 95 2 of the wrench, then when the wrench is applied to the nut and the two parts 2 and 12 drawn together by the action of the operator's hand, a pinching of the nut will result which is impossible to accomplish with 100 a common wrench.

While I have explained how a common nut may be thus forcibly grasped, it is evident that in the turning of many small objects like rods or pipes the same forcible 105 pinching may be accomplished, which will result in a very efficient wrench, and by the provision of the key 13 back of the recipro-

cal rack 4 the efficiency of the implement when used as a common wrench is in no wise impaired.

I have illustrated at 17 and 18 two cut-away portions in the cooperative jaws 3 and 14 which would result in the jaws being provided with common wire cutters; and it is apparent that in such case when the jaws 3 and 14 are adjusted by the worm 15 to impinge the wire to be cut and the handles 2 and 12 brought forcibly together an ideal cutting effect would result.

When the instrument is used as a vise, the jaws are drawn up as before to impinge the object when the pincer handles are opened, thus when closed they will hold the object firmly; and I have provided a pivotally suspended link 19 loosely hung in the extreme free end of the handle 12, which may be dropped down over the extreme end of the handle 2 and snapped into the recess 20 in said handle, where it will firmly hold the two together and the jaws thus permanently hold the object.

Having thus described my invention, what I claim and desire to secure by Letters Patent, is:

1. A wrench comprising in combination a main body portion having a fixed jaw upon one end thereof, a slidable jaw carried by the body portion, slidable means intermediate of the two jaws, separable therefrom and coactively uniting the same, and an arm-like member pivotally mounted in the body portion adjacent the fixed jaw and engaging the slidable means.

2. The combination with a mechanism as set forth in claim 1, of a key rigidly carried by the arm-like member for limiting the reciprocal movement of the movable jaw in one direction.

In testimony whereof I hereunto affix my signature in the presence of two witnesses.

ALBIN J. JOHNSON.
